UNITED STATES PATENT OFFICE.

JOSHUA BIDLACE, OF VICTORIA, BRITISH COLUMBIA, CANADA.

GANG-PLANK.

1,106,074.

Specification of Letters Patent.

Patented Aug. 4, 1914.

Application filed August 21, 1911, Serial No. 645,252. Renewed May 6, 1914. Serial No. 836,814.

To all whom it may concern:

Be it known that I, JOSHUA BIDLACE, a citizen of the United States, and a resident of Victoria, British Columbia, Canada, have invented certain new and useful Improvements in Gang-Planks, of which the following is a full, true, and exact specification, which will enable others skilled in the art to construct and use the same.

The principal object of this invention is to so improve the construction of extensible gang planks that the same may be more readily extended and collapsed and moved to and held at various angles; and that the entire structure may be also readily moved longitudinally of a ship so as to bring the gang plank in register with the ship's exit.

Other objects will appear as the invention is more fully described in the specification following, and shown in the accompanying drawings, in which—

Figure 1 is a side elevation of the device. Fig. 2 a rear end elevation, with the hinged approach removed. Fig. 3 an enlarged fragmentary side view of the ends of the telescoping sections. Fig. 4 a similar view in section upon the line $x-x$ of Fig. 1.

Referring now more particularly to the drawings, 1, 1^a and 1^b designate the sections of the gang plank, the section 1^a telescoping into the section 1 and the section 1^b telescoping into the section 1^a, the main bodies of each of the sections being box-like in form, as best shown in Fig. 4; the bottom 2 of the section 1 being extended somewhat at 3 so as to better support the sections when they are all fully telescoped into each other. Extending upwardly from the section 1 are the standards 4, connected by the rods 5. Similar standards 4^a extend from the section 1^a and which have one of the ends of the rods 5^a permanently secured to them at 6. The other ends of the rods 5^a are looped around the rods 5, as at 7, so as to slide freely therealong. Extending along the sides of the sections 1^a and 1^b are the ratchet teeth 8 with which coöperate the catches 9, held in place by the plate 10, and which are normally held against the teeth 8 by the spring 11. Upon the top of the catch 9 are the teeth 12 with which coöperates the latch 13. To the section 1 is rigidly secured the sector 14 which coöperates with the worm 15 which runs in the bearings 16 upon the plate 17 secured to the frame 18. The frame 18 is revolvably mounted upon the base frame 19 by means

of the pivot bolt 20. The frame 19 is mounted upon the traction wheels 21. The stem 22 of the worm 15 projects beyond the bearings 16 and has the large operating wheel 23 secured thereto. To the left hand end of the section 1 is hinged, at 24, the approach 24^a which is provided with the standards 25 and rods 26. The chains 27 connect one of the standards 25 with one of the standards 4 so that when the approach 24^a is let down as shown in Fig. 1 a convenient hand rail is afforded.

From the foregoing description it is believed that the construction and operation of my device will be fully understood by those skilled in the art.

It is obvious that when the plank is fully extended as shown in Fig. 1, a secure bridge is thereby formed from the wharf or other landing to the exit of a ship, or from the exit of one ship to that of another. It is also clear that if the exit of one ship is above or below the horizontal plane of the exit of the other ship or that of the wharf or other landing, the planks may be readily brought to the desired angularity by means of the worm 15 and its coöoperating sector 14 and so held by the same means together with the catches 9, teeth 12 and latches 13. If, upon landing, the exit of the ship should not coincide or register with the plank the latter may be moved along upon its wheels 21 and thereby nicely adjusted to the exit by means of its swivel action upon the bolt 12. When not in use the sections 1, 1^a and 1^b may be telescoped into each other, and when it is desired to extend these sections as shown in Fig. 1 all that is necessary is to turn the wheel 23 so as to bring the right hand end of the telescoped sections below the fulcrum 28, when the sections 1^a and 1^b will of themselves slide outwardly by gravity, the catch 9 riding freely over the teeth 8, until all the sections are fully extended, and locked in their extended positions by the catches 9 and teeth 8. By now turning the operating wheel 23 the extended sections 5 may now be still further lowered or raised to any desired angle and the approach 24^a thrown out to form a complete bridge. The plank may be readily collapsed by lifting the same to an upward angle and first withdrawing the catches 9 of the section 1^b from the teeth 8 and holding the same in that position by dropping the latch 13 into the teeth 12, which allows that section to slide back into

the section 1^a, when the section 1^a may be treated in the same manner. I have shown but three sections, but it is obvious that any convenient number of the same may be used with equal efficiency.

Many deviations in the details of the construction herein described are possible without departing from the spirit and scope of my invention, and I do not therefore desire 10 to be limited to the exact form herein described, and shown in the accompanying drawings.

Having described my invention what I claim as new and desire to protect by Letters 15 Patent is—

1. The combination in a gangplank of telescopic sections, ratchet and pawl means for holding said sections rigidly extended with relation to each other, a sector and co-operating worm for bringing said sections 20 so extended to various angles and holding

the same thereat, and a wheeled platform upon which said gangplank is revolubly mounted.

2. The combination in a gangplank of 25 telescopic sections, ratchet and pawl means for holding said sections rigidly extended with relation to each other, an upper frame in which one of said sections is revolubly mounted, a sector and co-operating worm for 30 bringing said extended sections to various angles, a wheeled base frame supporting said first mentioned frame and a pivot bolt connecting said frames to each other whereby the entire structure may be wheeled about 35 and said upper frame revolved upon said pivot bolt.

JOSHUA BIDLACE.
